ELECTRIC AIR HEATER

Mark H. Winner, Jr., New York, N. Y.

Application October 4, 1949, Serial No. 119,540

3 Claims. (Cl. 219—39)

1

This invention relates to heaters, and more particularly to an electric heater of the circulating-air type.

A main object of the invention is to provide a novel and improved electric air heater which is simple in construction, compact in size, and which provides a high volume of heated air per watt of electric energy dissipated.

A further object of the invention is to provide an improved electric air heater which is inexpensive to manufacture, which is neat in appearance, which is rugged in construction, and in which thermal losses are reduced to a minimum.

Further objects and advantages of the invention will become apparent from the following description and claims, and from the accompanying drawings, wherein:

Figure 1 is a side elevational view of a portable electric heater unit constructed in accordance with the present invention;

Figure 2 is a horizontal cross-sectional view taken on line 2—2 of Figure 1;

Figure 3 is a vertical cross-sectional view taken through the heater unit of Figure 1, parts being shown broken away;

Figure 4 is a vertical cross-sectional view taken on line 4—4 of Figure 3;

Figure 5 is a top plan view of the electric heater unit shown in Figure 1;

Figure 6 is an enlarged cross-sectional detail view taken through the lower U-bend of the heater air duct on the line 6—6 of Figure 2;

Figure 6a is an enlarged fragmentary detail cross-sectional view showing a portion of the air duct and illustrating a layer of insulation which may be employed on the outer surface thereof;

Figure 7 is an enlarged fragmentary detail cross-sectional view taken through one of the upper ends of the air ducts of Figure 6 in the plane of the duct, said view illustrating the manner of housing the electrical leads of the heating coil employed in the duct;

Figure 8 is a fragmentary perspective view of one end of the U-shaped duct of Figure 6.

Referring to the drawings, 11 designates a generally rectangular housing, which may be made of sheet metal or the like, the housing being provided with corner feet 12 which maintain the bottom wall of the housing in elevated position above the floor. Designated at 13 is an air intake duct secured to the bottom wall of the housing and opening into the space beneath the housing. Secured by suitable brackets, not

2

shown, in the duct 13 is an electric blower 14 arranged to draw air into the duct from the space beneath the housing.

As shown in Figures 3 and 4, the top portion 5 of intake duct 13 tapers upwardly, and connected to the top end of said duct is one end of an inverted U-shaped or connecting duct 15 making substantially a 180-degree bend. Connected to the other end of duct 15 is one end of 10 a U-shaped or second connecting duct 16, also making substantially a 180-degree bend, as shown in Figures 3 and 4. Connected to the other end of duct 16 is the lower end of an outlet duct 17, which has an upwardly-flaring top portion 15 connected to an outlet grille 18 secured in the top wall of housing 11.

The inner surfaces of the respective ducts 13, 15, 16 and 17 are preferably highly polished and more preferably nickel or chromium plated. 20 whereby said surfaces have high reflectivity to radiant energy. Therefore, the ducts absorb only a relatively small amount of radiant heat and reflect most of the radiant heat impinging thereon. As will be subsequently pointed out, the 25 ducts, and particularly duct 16, act as a shielding means to prevent loss of radiant heat from the heat source of the unit.

The respective ducts may be provided with a suitable outer coating of heat-insulating material, such as glass wool or the like, indicated at 30 19, to minimize external heat loss from the ducts by conduction and convection.

As shown in Figures 6, 7 and 8, the duct 16 has 35 the annular flanged collars 20, 20 secured to its ends for making connection to the similarly-flanged ends of the ducts 15 and 17. Secured inside the ends of the duct 16 are the radial tubular members 21, 21 and secured to the free ends of the tubular members 21, 21 are the respective sleeves 40 22, 22. The sleeves 22 extend at right angles to the tubular members 21 and are located axially of the conduit 16. Secured in the sleeves 22 are the respective ends of a semi-circular glass tube 23 extending axially through the duct 16.

As shown in Figure 7, set screws 24 are threaded 45 through the sleeves 22 and enter apertures 25 in the end portions of the glass tube 23, thereby rigidly supporting the glass tube in axial position in conduit 16. Designated at 26 is a helical heating coil wound helically on tube 23. Respective lead wires, shown at 27 and 28, are connected to the ends of the heating coil and extend inwardly through the ends of the glass tube, the tubular member 21, the inner portions 50 of the wall of duct 16 and the flanges of collars 55 of the wall of duct 16 and the flanges of collars

20, as shown in Figures 6 and 7. The lead wires 27 and 28 may be connected through a switch 29 carried by the top wall of housing 11 to a suitable source of current.

In operation, air is drawn into the intake duct 13 by the blower unit 14 and passes through duct 15 to duct 16, wherein the air is heated by conduction by contact with the heater winding 26. The heated air passes upwardly through duct 17 and is discharged from the top of housing 11 through the grille 18.

Most of the heat transferred to the air is obtained from the heating winding 26. The highly polished internal wall surfaces of the ducts reflect radiant energy back into the ducts, and in the case of duct 16, reflects the radiant energy back to the heater winding 26, whereby the heat energy is made available for direct transmission to the moving air current by conduction. Such heat as is absorbed by the internal walls of the ducts is also given up to the moving air current by conduction.

Since the heat loss from the system is minimized by the aforesaid reflective surfaces, a larger hourly volume of air may be forced through the ducts and heated to a desired temperature per watt of electric power dissipated in winding 26 than would be obtainable if said reflective surfaces were not employed. Therefore, the heater has a relatively high air-heating capacity, whereas its overall size and its wattage may be relatively small.

While a specific embodiment of a portable electric air heater has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A heater comprising a housing, an inlet duct at the bottom of the housing, an outlet duct at the upper portion of the housing, a curved duct in said housing connecting said inlet duct to said outlet duct, said curved duct comprising an inverted U-shaped duct member making a 180-degree bend, and an upright U-shaped duct member also making a 180-degree bend, the U-shaped duct members being joined together at their inner ends and said U-shaped members being

highly polished on their inner surfaces, a core element secured axially in one of said U-shaped duct members, an electrical heating coil carried on said core element, and blower means in said inlet duct.

2. A heater comprising a housing, an inlet duct at the bottom of the housing, an outlet duct at the upper portion of the housing, a curved duct in said housing connecting said inlet duct to said outlet duct, said curved duct comprising an inverted U-shaped duct member making a 180-degree bend, and an upright U-shaped duct member also making a 180-degree bend, the U-shaped duct members being joined together at their inner ends, a core element secured axially in one of said U-shaped duct members, an electrical heating coil carried on said core element, and blower means in one of the ducts.

3. A heater comprising a housing, a vertically disposed inlet duct positioned within said housing and having its lower end secured to the bottom of said housing and in communication with the atmosphere, a vertically disposed outlet duct positioned within said housing in side by side spaced relation with respect to said inlet duct and having its upper end supported in the top of said housing and in communication with the atmosphere, a first vertically disposed connecting duct positioned within said housing and having one end connected to the upper end of said inlet duct, a second vertically disposed connecting duct positioned within said housing and having one end connected to the other end of said first connecting duct and having the other end connected to the lower end of said outlet duct, a core element secured axially in one of said connecting ducts, an electrical heating coil carried on said core element, and blower means in one of said inlet and outlet ducts.
